UNITED STATES PATENT OFFICE.

JAMES D. MURPHY, OF BLACKFOOT, IDAHO.

PACK ANCHOR.

Application filed November 27, 1925. Serial No. 71,813.

My present invention has to do with the lashing or fastening of packs on the backs of pack animals; and it has for one of its objects the provision of a pack anchor, the 5 said anchor being adapted to be superposed on a pack on a horse's back and to be used in the maintenance of the pack in position without liability of the pack shifting, and this while conducing to the expeditious and 10 thorough fastening of the pack in such manner that while casual loosening or shifting of the pack is precluded, the pack may be quickly and easily released and removed when desired.

Other objects and practical advantages of 15 the invention will be fully understood from the following description and claims when the same are read in connection with the drawings, accompanying and forming part 20 of this specification, in which:

Figure 1 is a perspective showing my novel pack anchor in use.

Figure 2 is an enlarged horizontal section taken through the pack anchor and showing the arrangement of the lashing rope therein.

Figure 3 is an edge elevation of the pack anchor per se.

Similar numerals of reference designate 25 corresponding parts in all of the views of the drawings.

I show in Figure 1, a pack or bundle of merchandise 1 positioned on the back of a pack animal.

Also shown in Figure 1 is a belly band or surcingle 2, and a rope 3 in one piece, the said rope being permanently connected at one end 4 to the adjacent end of the belly band 2, and being designed at its opposite 35 end to be detachably connected to the other end of the belly band 2, the latter connection being of such character that the rope may be drawn taut while in engagement with the belly band or an eye at the end thereof, and the rope may then be tied for the tight fastening of the pack 1. The belly band 2 is shown in Figure 1 as provided with an eye, and therefore it will be understood that when desired both connections of 40 the rope 3 to the belly band 2 may be detachable and may also be adjustable.

My novel pack anchor is designed for use in superposed relation on and against the upper side of the pack 1 as shown in Figure 1, and the anchor is of such character 55 that the rope 3 may be relatively arranged

in the peculiar and advantageous manner hereinafter explicitly set forth.

Any material or materials compatible with the purpose of my invention may be 60 employed in the manufacture of the anchor, but I prefer for obvious reasons to have the anchor comprise upper and lower plates 5 of metal, the said plates 5 being fixedly connected together through the medium of connecting devices 6, and being maintained in spaced relation by interposed sleeves 7 or other appropriate means.

One of the plates 5 is provided at one end with an apertured portion 8 for the connection of one end of the rope 3 when such connection is deemed expedient, but in general I have found that it is most advantageous to arrange portions of the rope between the plates 5 and in contact with sheaves 9 mounted to freely rotate between the plates 5. Each of the plates 5 is gradually reduced in width or tapered from the middle thereof toward the ends, and therefore the anchor as a whole is tapered from 75 its intermediate portion to its ends, this being advantageous for reasons which will presently appear.

There are nine of the sheaves 9 employed, 80 and in the arrangement illustrated in Figure 2, which is in strict accord with my invention, a sheave 9 is located immediately adjacent to one end of the body formed by the plates 5, and pairs of sheaves 9 are arranged at opposite sides of and in spaced 85 relation to the transverse center of the said body. The anchor is intended to be arranged on a pack in the manner illustrated in Figure 1 so that the greatest length of the anchor is crosswise of the pack and at right angles to the pack animal, and in this connection it will be noticed that the portions of the rope 3 that extend from the anchor for connection with the ends of the belly band 2 are arranged alongside of and in contact with the end sheaves 9. It will also be noticed that one end portion of the rope 3 is arranged at one side of its respective sheave 9, and the other end portion of the rope is arranged at the opposite side of its respective sheave 9, so that the transverse portion of the rope tends to prevent casual movement or shifting of the anchor forwardly. The intermediate portion of the rope 3 is utilized to form loops 10 and 11 which are relatively arranged to the pack 1 as shown in Figure 1. Intermediate of the 90 95 100 105 110

two loops 10 and 11 the cable portion is carried as designated by 12 between the plates 5 of the body and obliquely thereof and in engagement with sheaves of opposite pairs at opposite sides of the body 5. Moreover a portion of one of the loops 10 is carried around another of the inner sheaves 9, and a portion of the loop 11 is carried around the remaining one of the inner sheaves so that when a pack is positioned on a pack animal, and the rope or cable 3 is relatively arranged as shown in Figures 1 and 2, and one end of the rope is fastened to the belly band 2, and the other end of the rope is subjected to pull for the purpose of tightening the lashing of the pack, the end portions of the loops will be drawn through the anchor in such manner that the rope will be rendered taut without alterations of the anchor on the pack and without shifting of the body of the anchor on and relative to the pack, it being noticed in the latter connection that there is always considerable frictional contact between the opposed surfaces of the anchor body and the pack 1.

My novel pack anchor has been used for a considerable period of time in the manner described in actual practice, and the said actual use of the improvement has demonstrated the fact that the anchor and the parts associated therewith are susceptible of quick and easy application, and are adapted to strongly hold the pack without liability of the pack shifting and yet when one end of the rope 3 is disconnected from the belly band, the anchor and the rope portions engaged therewith will not interfere in any appreciable measure with the release of the pack and the ready removal of the same from a pack animal.

I prefer the illustrated embodiment of my invention herein explicitly described for the reasons set forth. I do not desire, however, to be understood as confining myself to the specific construction and relative arrangement of parts as disclosed, my invention being defined by my appended claims within the scope of which changes in a structure and arrangement may be made without departure from my invention.

I would also have it understood that I do not confine myself to the specific arrangement illustrated of the rope 3. Manifestly instead of being arranged as shown in Figure 1, the rope 3, incident to the adjusting of the same to place, may be so manipulated that the end of the rope before being attached to the belly band may be placed under that portion of the top rope 3 which extends under the pack and between the pack and the body of the pack animal, this ar-

angement being materially advantageous inasmuch as it is calculated to prevent the pack from shifting or being displaced on the back of the pack animal.

Having described my invention, what I claim and desire to secure by Letters-Patent, is:—

1. A pack anchor comprising a body having spaced flat plates, said body being tapered toward opposite ends, sheaves mounted in the body and between said plates and arranged at points adjacent to the ends of the body, and pairs of sheaves arranged at opposite sides of the transverse center of the body and also arranged adjacent to the side edges of the body, all of the said sheaves being adapted for the free passage thereagainst of a rope.

2. A pack anchor comprising a body with portions spaced apart for the passage of a rope between the same, guides arranged between the said body portion and at points adjacent to the ends of the body, and pairs of guides also arranged between the body portion and at opposite sides of and in spaced relation to the transverse center of the body and at points adjacent to the side edges of the body.

3. A pack lashing comprising a rope, and a flat anchor including a body with portions spaced apart and arranged one above the other, sheaves mounted between the said portions of the body and arranged adjacent to the ends of the body, and sheaves interposed between the portions of the body and arranged at opposite sides of and in spaced relation to the transverse center of the body and also arranged adjacent to the side edges of the body, the said rope having terminal portions at opposite sides of the said end sheaves, and also having loops to receive a pack and loop portions in contact with the sheaves at the opposite sides of the body, and a portion intermediate of the two loops extending across the body and contacting with opposite side sheaves at points adjacent to opposite sides of the body.

4. A pack lashing comprising an anchor having a body with spaced portions, fixed guides positioned between the said portions, and a rope having portions extending in opposite directions through the anchor and each in contact with a guide at the opposite end of the anchor and also having loops and a portion between the loops and extending across the anchor and between the spaced portions thereof and in contact with guides at points adjacent to the opposite sides of the body.

In testimony whereof I affix my signature.

JAMES D. MURPHY.
